W. O. BECK

ELECTROMAGNETIC DEVICE

Filed June 20, 1921

Inventor:
William O. Beck
by *Jack C. Palmer* Atty.

UNITED STATES PATENT OFFICE.

WILLIAM O. BECK, OF RIDGEFIELD, NEW JERSEY, ASSIGNOR TO WESTERN ELECTRIC COMPANY, INCORPORATED, OF NEW YORK, N. Y., A CORPORATION OF NEW YORK.

ELECTROMAGNETIC DEVICE.

Application filed June 20, 1921. Serial No. 479,064.

To all whom it may concern:

Be it known that I, WILLIAM O. BECK, a citizen of the United States, residing at Ridgefield, in the county of Bergen, State of New Jersey, have invented certain new and useful Improvements in Electromagnetic Devices, of which the following is a full, clear, concise, and exact description.

This invention relates in general to electromagnetic devices and more particularly to a relay having high sensitivity and operable at high speeds.

In connection with various circuit arrangements, such for example, as the circuits employed for high speed telegraphy, there is a demand for a relay which will operate satisfactorily with very low operating currents, and which will maintain its adjustment constant over considerable periods of time. Since such a relay is not only called upon to operate with low operating current values, but is also required to operate at high speeds, it becomes necessary to make the travel of the vibrating member very small, and it is, therefore, essential that means be provided for insuring a very fine adjustment and maintaining this adjustment constant during service. Moreover, to provide such an adjustment it is necessary that a structure be employed in which there is no backlash and in which the parts are not subject to wear in such a manner as to interfere with the adjustment.

It is, therefore, an object of the present invention to provide a relay in which the adjusting mechanism is very sensitive, easily manipulated, and not subject to changes during operation of the device.

It is a further object to provide a structure in which the contact members are easily accessible for the purpose of construction or repairs.

It is a still further object of the invention to provide a simple structure in which the adjustable contacting devices may be held in position and locked in adjustment.

To accomplish these objects, and in accordance with a feature of the invention, there is provided a relay having adjusting devices in which the parts are rigidly connected to adjoining parts in such a manner as to permit no backlash or possible movement due to wear of the parts. In accordance with another feature of the invention, the contact screws are mounted on a pivot

plate, and flexible connections are provided so that the plate may be swung out of alignment with the armature to permit cleaning or inspection of the contacts. In accordance with another feature of the invention, means is provided for simultaneously locking the contact screws and supporting plates in position.

These and other features of the invention will be more clearly understood by reference to the accompanying drawing in which Fig. 1 is a perspective view of a relay embodying the features of this invention; Fig. 2 is a view in perspective showing more clearly the method employed for adjusting; and Fig. 3 is a cross-sectional view taken along the line 3—3 of Fig. 1, showing the manner in which the contact screws are held in place.

Referring now to the drawing, there is provided a base 10 of hard rubber or similar insulating material, upon which is secured a metal mounting plate 11. Secured to this plate, by means of screws 12, 12, but insulated therefrom by means of plates 13 and bushings 14 of insulating material, is a supporting member 15 of non-magnetic material. Secured to the central portion of this member is a polarized relay of the general type described in detail in Patent 1,339,778, consisting essentially of a polarized magnet 16, adjustable pole pieces 17, 17, armature 18, and operating coils 19, 19. The upper portion of the member 15 is provided at 20 with an off-set portion to receive the segment 21, which is preferably of phosphor bronze or hard spring brass and is rigidly secured to the member 15 by means of screws 22, 22. The segment 21 is slotted as shown in Fig. 2, to provide a triangular shaped portion 23, separated from the main portion by means of a tongue portion 24 of restricted cross-section to obtain proper flexure. Rigidly secured to the triangular portion 23 by means of screws 25, is a plate member 26 upon which the support 27 is rigidly supported. Pivoted secured to this support by means of the pivot screws 28, 28, is the bridge member 29, upon which are mounted contact posts 30, 30. These posts, which are provided with horizontal slots and threaded to receive the contact screws 34, 34, are insulated from the bridge member by means of insulating plates 31, 31 and are held in position by means of the

screws 32 and 33. The screws 33 are arranged to engage suitable threads in the posts below the slots but to pass freely through the portions above the slots. Internally threaded caps or nuts 35, provided with shouldered heads, are adapted to engage the threaded portions of screws 33 and serve the double purpose of locking the screws 33 in position and also the adjusting screws 34, 34, thus eliminating the necessity for additional locking screws. The plate 26 is provided with an opening 36 through which extends the armature 18, and suitable oblong slots 37, 37 are provided through which pass the insulated conductors 38 leading to the screws 33. During operation, the bridge member 29 is held in the proper position so that the contact screws are in alignment with the contact points of the armature by means of distance pins 39, 39, and a shouldered locking screw 40. When it is desired to inspect the contact points, the screw 40 may be loosened and the bridge member rotated about the pivot screws 28, 28, throwing the bridge members in a vertical position and thus leaving all the members open for inspection.

Passing through suitable bearings 41 in member 15 is a vertical shaft 42, which is provided at its upper end with a cam shaped collar 43 engaging a roller 44, rotating about a trunnion screw 45 secured in the plate member 26. At the lower end of shaft 42, there is provided a lever 46 having a right-angled pin 47 extending therefrom. The lever 48, pivotally secured to the plate 11 by means of the screw 49, is provided with an insulated section 50 which is adapted to engage the pin 47. These parts are held in continual engagement by means of the spring 51, which is secured between the pin 47 and a second pin 52 rigidly secured to plate 11. The knurled head adjusting screw 53 passes through a suitable opening in the base 10 and its threaded portion is adapted to engage with the threads of a post 54, which is rigidly secured to the plate 11. The end of adjusting screw 53 engages with lever 48 which, in turn, engages pin 47 of lever 46 and thus causes the rotation of shaft 42. Upon the rotation of shaft 42, due to turning of adjusting screw 53, the cam portion 43 actuates the roller 44, causing a flexure of the tongued portion 24, thus effecting a lateral movement to the plate 26 with respect to the supporting member 20. By this arrangement, although the various parts are rigidly connected together, there is sufficient flexure to permit the plate 26 being rotated an amount sufficient to provide the necessary movement between the contact screws 34, 34 and the armature 18. Suitable binding post terminals 56, 56 are provided in the base member 10, to which are connected

the various windings of the coils 19, 19, the contact screws 34, 34, and the armature 18. The adjusting screw 53 is preferably provided with marking as shown to designate the direction for turning to increase the length of the mark or space when the relay is operated in connection with recording apparatus employing a tape. 70

It will be noted that the structure, as described, eliminates backlash and does not contain any parts which, due to wear, could in any way change the adjustment of the device. Furthermore, the biasing adjustment does not change the distance between the contact screws 34, 34 when these screws 80 are once properly positioned, thus differing from the constructions ordinarily employed in which biasing is obtained only by moving both adjusting screws an equal amount. With a device of this type, it has been found possible to obtain an adjustment which is extremely sensitive and accurate and which is maintained in service in spite of the continual vibrations due to the operation of the armature. While in service a dust-proof cover is provided to fit upon the base 10 outside the plate 11, and is held in position by means of lugs 55 in order to avoid confusion; this cover is not shown in the drawing. 95

What is claimed is:

1. An electromagnetic device comprising an operating coil, a support therefor, an armature, a contact member engaged by the operation of said armature, a support for 100 the contact member, and contact adjusting means including a plate member rigidly connected to each of said supports but having a flexible portion to permit movement of the supports with respect to each other. 105

2. An electromagnetic device comprising an operating coil, a support therefor, an armature, a contact member positioned on either side of and adapted to be engaged by the operation of the armature, a support for 110 said contact members, said support being pivotally mounted to rotate clear of the armature, and adjusting means for adjusting the position of said contacts with respect to the armature without changing the 115 separation between the contact members.

3. An electromagnetic device comprising an operating coil, a support therefor, an armature, a contact member engaged upon the operation of said armature, a support 120 for the contact member, said support being pivotally mounted to rotate vertically about a horizontal axis, means for adjusting the position of the contact members with respect to the armature, and additional means 125 rigidly connected to the contact support for further adjusting the position of the contact member with respect to the armature.

4. An electromagnetic device comprising an operating coil, a support therefor, an 130

armature, a pair of contact members mounted upon the opposite sides of and adapted to be engaged by the operation of the armature, a support for the contact members, said support being pivotally mounted to rotate vertically about a horizontal axis, means for adjusting the position of each contact member with respect to the armature, and additional means rigidly connected to the contact support for further adjusting the position of the contact members with respect to the armature without changing the separation between said contact members.

5. A relay comprising an electromagnet, an armature therefor, a supporting member for the electromagnet, a contact member engaged by the operation of the armature, a supporting member for the contact member, said supporting member being pivotally mounted to rotate vertically about a horizontal axis, and means for adjusting the position of the contact member with respect to the armature, said adjusting means being rigidly connected to each of said supporting members but providing a flexible connection therebetween.

6. A relay comprising an electromagnet, an armature therefor, a support for the electromagnet, a contact member engaged by the operation of the armature, a supporting plate for the contact member, an intermediate member rigidly secured to each of said supporting members, and means for causing the flexure of said intermediate member.

7. A relay comprising an electromagnet, an armature therefor, a support for the electromagnet, a contact member engaged by the operation of the armature, a supporting plate for the contact member, an intermediate member having its central portion joined to its outer portion by a tongue portion of restricted cross-section, the outer portion of this member being connected rig-

idly to the electromagnet-supporting member, the inner portion being connected rigidly to the contact supporting member, and means for causing the flexure of said intermediate member at the restricted portion.

8. A relay comprising an electromagnet, an armature therefor, a support for said electromagnet, a pivoted arm carrying a pair of opposed contacts adapted to be engaged in alternative positions of the armature, said arm being mounted so that it may be swung clear of the armature and again swung back into operating position without destroying the adjustment of said contacts.

9. A relay comprising an electromagnet, an armature therefor, a contact member adapted to be engaged by the operation of the armature, a contact screw, a contact plate having a horizontal slot therein provided with a threaded portion to engage said contact screw, means for securing the contact plate to a supporting member, and means for simultaneously locking the securing means for said contact plate and clamping the contact screw in the clamping plate.

10. An electromagnetic device comprising an operating coil, a support therefor, an armature, a contact member engaged upon the operation of said armature, a supporting plate for said contact member, a flexible intermediate member rigidly connected to said plate and to the support, a shaft rotatably mounted in said support and having a cam at one end adapted to engage a roller rotatably mounted upon said plate, and means for causing the rotation of said shaft to alter the position between the contact member and the armature.

In witness whereof, I hereunto subscribe my name this 16th day of June, A. D. 1921.

WILLIAM O. BECK.
